UNITED STATES PATENT OFFICE.

THOMAS J. WORSTELL, OF ST. LOUIS, MISSOURI.

DESIGN FOR A TOY BALLOON.

Application filed August 13, 1923. Serial No. 6,997. Term of patent 14 years.

To all whom it may concern:

Be it known that I, THOMAS J. WORSTELL, a citizen of the United States, residing at St. Louis, in the State of Missouri, have invented a new, original, and ornamental Design for a Toy Balloon, of which the following is a specification, reference being had to the accompanying drawing, forming part thereof, wherein is shown my new design.

Description of figures.

Fig. 1 is a perspective view of a toy balloon showing my new design.

Fig. 2 is a front elevation, and

Fig. 3 is a side elevation thereof.

I claim:

The ornamental design for a toy balloon as shown.

THOMAS J. WORSTELL.
